UNITED STATES PATENT OFFICE.

FREDERIC A. SKIFF, OF PAXTON, MASSACHUSETTS.

HOISTING MECHANISM.

1,069,195.

Specification of Letters Patent.

Patented Aug. 5, 1913.

Application filed September 11, 1912. Serial No. 719,885.

To all whom it may concern:

Be it known that I, FREDERIC A. SKIFF, a citizen of the United States, residing at Paxton, in the county of Worcester and State of Massachusetts, have invented certain new and useful Improvements in Hoisting Mechanisms, of which the following is a specification.

This invention relates to hoists.

10 The primary object of the invention is to provide a hoisting mechanism in which the article to be lifted may be raised with a small amount of exertion on the part of the operator, the construction being such that 15 one operator may position and manipulate the entire mechanism.

A further object of the invention is to provide a construction in which the lifting mechanism may be locked against movement 20 at any desired height.

A still further object of the invention is to provide means whereby the pull is exerted in a direct vertical line.

In the drawings: Figure 1 is a perspective view; and Fig. 2 a detail view of the shaft which forms the winding drum.

In the drawings 10 designates a frame which consists of the beam 11 to which is bolted a beam 12, the terminals of the beam 30 12 being off-set. The terminal 14 of the beam 12 is bent to embrace the upper terminal of the beam 11, the terminal 16 of said beam being secured to the beam 11 in spaced relation with respect to its lower terminal 35 17. The off-setting of the terminals of the beam 12 space the intermediate portions 18 and 19 of the beams 11 and 12, forming a housing for the gears 20 and 21. The smaller gear is mounted on a shaft 22, the terminal 40 of which projects beyond the beam 12, the crank 24 being secured to said terminal.

The major gear 20 which meshes with the gear 21 is mounted on the shaft 25. The portion of the shaft 25 which extends 45 through the beams 11 and 12 is round in cross-section, the portion 26 of said shaft which constitutes the winding drum being square in cross section. A ring 29 is secured to the lower terminal 17 of the beam 12, the article lifted being connected to said ring. A ring 30 is secured adjacent the meeting 50 upper terminals of the beams 11 and 12, the bolt 31 which supports the ring passing through the beams 11 and 12, its terminal remote from the beam 11 supporting a chain 55

32 which is provided with the hook 33. A chain 34, both terminals of which are provided with rings which prevent its being passed entirely through the ring 30, is connected at one of its ends with a suitable support, its other end being passed through the ring 30 and secured to the shaft 25. This chain is connected to the shaft 25 by passing one of its links between the bifurcations 25' of said shaft. These bifurcations are substantially triangular in cross section, and the apexes of the triangles serve to prevent the displacement of the chain, contacting with the adjacent links. 60 65

When it is desired to lift an article which 70 has been previously attached to the ring 29, the crank 24 is rotated causing the chain 34 to wind upon the shaft 25, thus the chain is shortened and the article is lifted, the winding of the chain on the shaft 25 causing 75 the frame to travel on the chain 34. While the device is shown as equipped with a crank for rotating the gears, it will be noted that a suitable mechanism may be employed to operate the gears from a point 80 remote from the frame. When it is desired to stop the hoist with a load in position, the hook 33 of the chain 32 is either inserted in one of the links of the chain 34, or brought to a position to embrace the 85 crank 24. It will be noted by this construction that the frame may be conveniently supported against movement even though the load be attached to its lower terminal.

Particular attention is called to the fact 90 that although the actual winding of the chain occurs at a point out of vertical alignment with the frame, the ring 30 which is secured adjacent the upper terminal of the frame properly centers the weight with respect to the frame. 95

The many advantages of a construction of this character will be clearly apparent, as it will be noted that the same provides a mechanism which may be conveniently attached to a suitable support and to the article to be lifted. 100

It will be seen that the construction is such as may be easily and economically manufactured and that the various parts 105 may be readily assembled. It will also be noted that the device provides a durable construction which will not readily get out of order and which will occupy but comparatively small space when not in use. 110

Having described my invention, what I claim as new is:

A hoisting mechanism including a frame comprising spaced terminally connected members, shafts supported by said members, a pinion mounted on one of said shafts, means for rotating said shafts, a gear mounted on the other shaft and meshing with said pinion, a ring secured to the upper terminal of said frame, a securing device for said ring passing through the beams which constitute the frame, a chain

supported by said securing device, a lifting chain, said chain being passed through said ring and connected to said shaft, the chain which is supported by said securing device being adapted to engage the second chain to lock the frame against movement.

In testimony whereof I affix my signature in presence of two witnesses.

FREDERIC A. SKIFF. [L. S.]
